UNITED STATES PATENT OFFICE.

LOUIS FREDERICK KLOOZ AND MANNING F. HATCHER, OF PITTSBURGH, PENN.
SYLVANIA.

WINDOW FASTENER.

Application filed November 10, 1926. Serial No. 147,429.

The principal object of this invention is to provide sliding window sashes with fastening means which will couple the upper and lower sashes together with the upper

5 sash in any position of adjustment, and which will prevent opening movement of either sash when so coupled together.

With this and other equally important objects in view, as will hereinafter be pointed 10 out, reference will be had to the accompanying drawing forming a part of this specification and wherein like reference numerals designate corresponding parts throughout the several views, in which:—

15 Fig. 1 is a vertical sectional view of a fragment of a window frame and its two sashes, with the invention applied and shown in unfastening position,

Fig. 2 is a front elevation thereof,

20 Fig. 3 is a perspective view of the fastening element disassembled, and

Fig. 4 is a vertical sectional view through the invention detached from the sash.

In the drawing, reference character 25 designates the window frame provided with the usual ways 3 and 4 for the sliding sashes 5 and 6, and with the usual parting strip 7, except that the latter is provided with a notch 8 just above the plane of the meeting 30 rail of the lower sash when the latter is completely lowered. Of course it will be understood that the parts 3, 4, 7 and 8 are duplicated on the other side of the window as is usual. Upon the meeting rail of the lower 35 sash 5 at each side of the window is provided the sash fastening device forming the foundation of this invention, and except for the fact that one is right handed and the other left handed, their structures are the same, and detailed description of one will suffice for the other. Each fastening device 40 comprises a bearing member 9, formed by doubling a sheet of metal to enfold a rock-shaft 10, and having a base 12 and cut-out 45 portion 14 within which latter operated the thumb or finger knob 15. This rock-shaft 10 has its opposite side portions cut away as at 16 leaving a reduced flat web 17 provided with a threaded aperture 18 in which threads 50 the stem 19 of the knob 15. A ribbon spring 20 has its free end bearing upon the base 12 and, after bending around the web 17, has its upper end secured between said knob 15 and web 17, with the knob stem 19 passed

therethrough. The outer end of the rock-shaft 55 is formed with a right angular foot portion 21 having teeth 22 formed on its toe end.

When the device of Fig. 4 is assembled, one on each side of the lower sash, the 60 springs 20 will swing the foot ends 21 through the parting strip notches 8 into biting engagement with the face of the side rails of the upper sash, thereby fastening the upper sash to the lower sash and because 65 of the toe ends of the fastening devices coming into engagement with the upper walls of the notches 8, preventing raising of the lower sash. This coupling together of the two sashes will prevent lowering of the upper 70 sash, though it will permit raising of the upper sash at any time to closed position. If the upper sash is somewhat lowered when the two sashes are coupled together, the two sashes cannot be raised as a whole to permit 75 an intruder reaching in beneath the lower sash for any purpose, because such movement of the sashes is prevented by contact of the fastening devices with the upper wall of the notch 8. When it is desired to raise the lower sash, the operator depresses both knobs 15 thereby swinging the foot ends of the fastener to the full line position of Fig. 1, wherein there will be no engagement with the upper wall of the notch by the foot ends 80 21, and as the lower sash is raised, these foot ends will freely ride along the faces of the parting strips 7 without effecting fastening 85 engagement and without marring the surface thereof. It will be obvious that the continual biting of the toe end 22 of the fastening device will more or less mar the surface of the side rails of the upper sash, but this defacement will be concealed almost entirely by the overlying parting strips 7 and the foot 90 ends 21.

Thus it will be apparent, that the upper sash may be lowered for ventilation, and yet secured against any but closing movement, while the lower sash is secured against any 100 movement, until the fastenings are manually moved to unfastening positions, when both sashes may be moved as in any other window of the same general type. It will also be apparent that the invention can be cheaply 105 made and easily applied, and that it cannot be "picked" by an intruder from the outside, and since the only alteration necessary to

be made in a standard window is the notching of the parting strips 7, the invention can be applied to old as well as to new windows.

What is claimed is:—

- 5 1. The combination with upper and lower sliding window sashes and a parting strip having a notch about midway of its length, of a bearing member mounted on the upper rail of the lower sash, a substantially L-shaped latching member having an arm pivotally mounted in the bearing member for movement about a horizontal axis, and having another arm arranged beyond one end of said bearing member and adapted to slide 10 along the parting strip, or to extend through the notch of the latter, to engage one wall of said notch for preventing the lower sash being raised, the extremity of said last mentioned arm being milled to wedgingly en-
- 15

gage a surface of the upper sash, and the 20 portion of this surface engaged by the milled face being entirely concealed by the parting strip, with the exception of the portion visible through said notch, and a handle connected to the latching member.

2. A combination as claimed in claim 1, in which the first mentioned arm of said latching member is provided with an intermediate portion arranged within the bearing and a leaf spring having one of its ends 25 secured to said intermediate portion and its other end contacting with the bearing for urging the latching member into securing position.

In testimony whereof we affix our signatures.

LOUIS FREDERICK KLOOZ.
MANNING F. HATCHER.
